WARNING SIGNAL

Jack Insul, Chicago, Ill.

Application April 13, 1945, Serial No. 588,229

5 Claims. (CL. 116—125)

1

This invention relates to a gas stove warning signal and, more particularly, to warning signals which may be employed upon a household gas stove for the purpose of indicating that the gas valve control handle, and the gas valve controlled thereby, are in an open, or partially open, position.

It has been found from experience that the gas valves of household gas stoves may be disposed in a partially opened position and cause sufficient leakage of gas to be dangerous without causing sufficient gas flow to be ignited by the usual, pilot light or lights employed in connection with such gas stoves.

Accordingly, an object of the present invention is to provide a new and improved gas stove warning signal which is so constructed and arranged that it will positively indicate that the gas valve with which it is employed is in an open, or partially open, position even though the pilot light employed in conjunction therewith is not ignited.

Another object of the invention is to provide a new and improved gas stove warning signal which is readily visible at night, or in dark places, as well as being readily visible in the daytime.

Other objects of the present invention will be apparent from the following description and claims and are illustrated in the accompanying drawing which, by way of illustration, shows preferred embodiments of the invention and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

Fig. 1 is a perspective view of a household gas stove having a preferred form of the present invention associated therewith;

Fig. 2 is a front elevational view of a preferred form of the present invention as associated with a gas stove valve control handle and showing the said handle, and the new warning signal associated therewith, as they appear when the handle is in valve-closing position;

Fig. 3 is a side elevational view of the gas valve control handle and associated warning signal illustrated in Fig. 2;

Fig. 4 is a view partly in section and partly in elevation of the gas valve control handle and associated warning signal illustrated in Figs. 2 and 3 but showing the warning signal in effective or warning position;

2

Fig. 5 is a horizontal sectional plan view showing the socket provided in the gas valve control handle and the gravity-attracted warning element or ball arranged therein and showing the warning element or ball in the position which it assumes in the said socket when the gas valve control handle is in its normal and valve-closing position;

Fig. 6 is a horizontal sectional plan view on line 6—6 in Fig. 4 showing the position of the parts illustrated in Fig. 5 when the gas valve control handle is in valve-opening position;

Fig. 7 is a view partly in section and partly in elevation illustrating a modified form of the invention; a part of the handle being broken away to show the interior thereof;

Fig. 8 is a front elevational view illustrating another modification of the invention and showing the parts thereof in the position in which they are arranged when the gas valve control handle is in valve-closing position;

Fig. 9 is a view of the parts shown in Fig. 8 in the position which they assume when the gas valve control handle is in open position, part of the front wall of the outer cylindrical handle member being broken away to show the internal construction of the parts;

Fig. 10 is a sectional plan view on line 10—10 in Fig. 8; and

Fig. 11 is a sectional view on line 11—11 in Fig. 5 showing the normal position of the gravity-attracted warning signal ball.

A preferred form of the invention is illustrated in Figs. 1 to 6, inclusive, and Fig. 11, of the drawings and is therein shown as associated with the gas valve control handle 15 of a conventional gas stove 16. Gas valve control handles, such as 15, are commonly made of porcelain, or like material, and comprise a body 17 in which an opening is provided for the reception of a gas valve control shaft 18, of conventional design.

In the form of the invention shown in Figs. 1 to 6, inclusive, and Fig. 11 I provide in the porcelain body 17 of the gas valve control handle 15 a normally horizontally extending socket 19 which extends inwardly from one side edge 20 of the handle 15 to a point within the interior of the handle body 17. At its outer end this socket 19 is closed by a convex transparent glass or plastic sight opening or window 21 which projects outwardly at the side 20 of the handle body 17. In this form of the invention I arrange within the socket 19 a gravity-attracted warning signal element in the form of a ball 22.

In the use of the form of the invention shown in Figs. 1 to 6, inclusive, and Fig. 11, the gravity-

attracted warning signal element or ball 22 is normally disposed at the inner end of the socket 19 when the gas valve control handle 15 is in its normal and valve-closing position, as in Figs. 2, 3, 5 and 11. To this end the socket 19 is then inclined slightly from the horizontal as shown in Fig. 11. However, when the gas valve control handle 15 is moved into valve-opening position, as in Figs. 4 and 6, the gravity-attracted warning signal element or ball 22 travels by gravity to the outer end of the socket 19 and falls into the convex transparent sight opening or window 21 and when disposed in this position it may readily be seen and indicates that the gas valve control handle 15 is in at least partially opened position.

In order to enable the gravity-attracted warning signal element or ball 22 to be seen at night, or in dark places, the ball 22 may be coated with luminescent or phosphorescent paint or the like and, further to increase the visibility of the ball 22, the sight opening or window 21 may be made of a magnifying glass or like material.

A modification of the invention is illustrated in Fig. 7 and those parts thereof which correspond to similar parts in the form of the invention illustrated in Figs. 1 to 6, inclusive, and Fig. 11, have been given similar reference numerals followed by the additional reference letter "a."

In the form of the invention shown in Fig. 7 I mount upon the gas valve control shaft 18a a gravity-attracted warning signal element, which is generally indicated at 23, and which is in the form of a pendulum having a cylindrical hub or bearing portion 24 which floats upon the shaft 18a. The pendulum warning signal 23 also has a pendulum weight 25 at its lower end and at its upper end it is provided with a preferably red colored warning signal or flag 26.

In the form of the invention shown in Fig. 7 I provide in the body 17a of the handle 15a a cavity 21 and in one side wall of the body 17a of the handle 15a I provide an opening or slot 28 which extends into the cavity 21 whereas in the opposite side wall of the body 17a of the handle 15a I provide an opening or slot 29 which extends into the cavity 27.

In the use of the form of the invention shown in Fig. 7 the gravity-attracted warning signal element 23 is at all times suspended in vertical position by means of its pendulum weight 25 and is entirely concealed within the cavity 21 in the handle body 17a when the handle 15a is in normal or valve-closing position. However, when the handle 15a is turned in a position to move the gas valve control shaft 18a into valve-opening position, as shown in Fig. 7, the warning signal element or flag 26 projects outwardly through the opening or slot 29 so that it may readily be seen and thus indicates that the handle 15a and the gas valve control shaft 18a are in valve-opening position. However, when the handle 15a and the gas valve control shaft 18a are returned to normal or valve-closing position the warning signal element or flag 26 will again pass through the opening or slot 29 into the cavity 27 in the body 17a of the handle element 15a.

It will be noted that in the use of the form of the invention shown in Fig. 7 the pendulum weight 25 is likewise normally disposed within the cavity 27 in the body 17a of the handle element 15a when the handle 15a and the gas valve control shaft 18a are in normal or valve-closing position. However, when the handle 15a and the shaft 18a are moved into valve-opening position,

as in Fig. 7, the pendulum weight 25 passes through the opening or slot 28 into the position in which it is shown in Fig. 7. However, when the handle 15a is again returned to normal position the pendulum weight 25 returns through the opening or slot 28 into the cavity 27 in the body 17a of the handle 15a.

Another modification of the invention is illustrated in the Figs. 8, 9 and 10 and is therein generally indicated at 30. This form of the invention is shown as being associated with the gas valve control shaft 18b of a gas valve of a gas stove such as 16.

In the form of the invention shown in Figs. 8, 9 and 10 I mount upon the gas valve control shaft 18b, for rotation therewith, a substantially cylindrical handle member or knob 31 having a disk-shaped front wall 32 which is provided with a row of sight openings 33. This cylindrical handle member 31 has an inwardly extending cylindrical hub portion 35 which may be attached to the shaft 18b in any suitable manner and which is attached at its front end to the disc-shaped front wall 32 of the cylindrical handle member 31. In this form of the invention I also provide, within the substantially cylindrical outer and handle member 31, a second substantially cylindrical member 34 having a cylindrical hub portion 35 which floats upon the smaller hub portion 36 of the outer cylindrical handle member or knob 31 which is attached to the shaft 18b. Attached to and suspended from the hub portion 35 of the inner cylindrical member 34 is a weight 37. The inner cylindrical member 34 also includes a disc-shaped front wall 38 which is provided with a row of preferably red colored warning signal areas or segments 39.

In the use of the form of the invention shown in Figs. 8, 9 and 10 the inner cylindrical handle member or knob 34 and its hub portion 35 float upon the smaller hub portion 36 of the outer cylindrical handle member or knob 31 and are maintained by the pendulum or weight 37 in such a position that the red colored warning signal areas 39 provided on the disc-shaped front wall 38 of the inner cylindrical member 34 are disposed out of registration with the sight openings 33 in the front and disc-shaped wall of the outer cylindrical handle member or knob 31. However, when the outer cylindrical handle member or knob 31 and the shaft 18b operated thereby are turned into valve-opening position the sight openings 33 in the front wall 32 of the outer cylindrical handle member or knob 31 are moved into registration with the red colored warning signal areas or segments 39 on the front wall 38 of the inner cylindrical member 34, thereby rendering the said red colored warning signal areas 39 visible and thereby indicating that the handle member 31 and the gas valve control shaft 18b operated thereby are in valve-opening position, and that the gas valve controlled thereby is in at least partially open position.

It will thus be seen from the foregoing description, considered in conjunction with the accompanying drawing, that the present invention provides a new and improved gas stove warning signal device, and thus has the desirable advantages and characteristics, and accomplishes its intended objects, including those hereinbefore pointed out and others which are inherent in the invention.

Hence, while I have illustrated and described the preferred embodiments of my invention, it is to be understood that these are capable of varia-

tion and modification and I therefore do not wish to be limited to the precise details set forth, but desire to avail myself of such changes and alterations as fall within the purview of the following claims.

I claim:

1. A gas stove warning signal, comprising a rotatable gas valve control shaft, a manually operable control handle mounted upon the said gas valve control shaft and having an elongated socket formed therein and the said socket having an end portion providing a sight opening therein, and a gravity-attracted warning signal element in said socket, said gravity-attracted signal element being normally disposed in a substantially concealed position in said socket but moving by gravity into the portion of said socket providing said sight opening when the said gas valve control handle is manually moved into a position to move the said gas valve control shaft into valve-opening position.

2. A gas stove warning signal device as defined in claim 1 in which said gravity-attracted warning signal element embodies a substance rendering it self-luminous so that it may readily be seen in the dark when the said gravity-attracted warning signal element is disposed in that portion of the said socket which provides the said sight opening.

3. A gas stove warning signal device as defined in claim 1 in which said handle comprises a porcelain body and in which the said socket is formed in the said porcelain body of the said handle and in which the said socket has a transparent window at one end thereof providing the said sight opening therein.

4. An on-off indicator for indicating the rotary position of a control shaft rotatable between a normal position and an actuated position, said indicator comprising a manually operable control handle adapted to be operatively mounted upon said control shaft for moving said shaft between said normal and actuated positions, an elongated socket disposed in said handle, said socket having a transparent end portion providing a sight opening, and a gravity-attracted warning signal element mounted in said socket, said

signal element being normally disposed in substantially concealed position in the opposite end portion of said socket from said one end portion but moving by gravity into exposed position in said one end portion of said socket when said control handle is moved to rotate said shaft from said normal position to an actuated position.

5. An on-off indicator for indicating the rotary position of a control shaft rotatable between a normal position and an actuated position, said indicator comprising a manually operable control handle adapted to be operatively mounted on such a shaft for moving said shaft between said normal and actuated positions, an elongated socket disposed in said handle, said socket having a transparent end portion projecting outwardly from said handle to provide a sight opening, and a gravity-attracted warning signal element mounted in said socket, said gravity-attracted signal element being normally disposed in a substantially concealed position within said handle but moving by gravity into said end portion of said socket when said handle is manually rotated to rotate said shaft from said normal position to said actuated position.
